DESIGN FOR AN INFANT'S PLAY SUIT

Besse S. Jetmore, Olathe, Kans., assignor to The Grace Company, Belton, Mo., a corporation of Missouri

Application December 30, 1940, Serial No. 97,721

Term of patent 14 years

To all whom it may concern:

Be it known that I, Besse S. Jetmore, residing at Olathe, in the county of Johnson and State of Kansas, have invented a new, original, and ornamental Design for an Infant's Play Suit, of which the following is a specification, reference being had to the accompanying drawing forming part thereof, in which,

Figure 1 is a front elevation of an infant's play suit, showing my new design.

Figure 2 is a rear view of the play suit shown in Figure 1.

The characteristic features of my design reside in an infant's play suit having a bib of the configuration shown in combination with full length leg portions and a high waist line, said waist line having pleats extending downwardly from the front thereof and darts extending downwardly from the rear thereof, all as shown.

I claim:

The ornamental design for an infant's play suit, substantially as shown and described.

BESSE S. JETMORE.
